CENTER SILL

William F. Kiesel, Jr., Hollidaysburg, Pa.

Application July 16, 1935, Serial No. 31,576

17 Claims. (Cl. 105—418)

This invention relates to center sill construction for cars and of the type that extend lengthwise thereof and substantially midway between the opposing side frame members, while it has more particular reference to a novel form of such sill that is preferably adapted for embodiment in railroad drop-bottom cars wherein it is highly desirable that all projecting parts in the region of the shedding surfaces be reduced to a minimum or totally eliminated.

An important object of this invention is to provide an open-bottom center sill including draft extensions and bolster flanges as a continuous integrally-formed structure, such center sill being of varying cross-sectional shapes at different parts of the length, whereby its incorporation in car frames is easily effected and, due to its novel formation and shape, provides good clearing angles and smooth surfaces in the outlet region or regions.

Another object of this invention is the provision of a center sill characterized by great strength and rigidity which is fabricated without any special housing, or analogous structural addition, within the hopper space and thereby effecting a saving in weight, cost and space.

A further object is to provide a center sill embodying counterpart plate components extending the entire length of said sill, such components being integrally-united along their upper confronting longitudinal edges.

A still further object is to provide an all plate center sill which by virtue of predetermined cross-sectional shaping of its counterpart components is adequately stiffened to resist the usual service strains and stresses common to railroad cars of the above mentioned types.

With the foregoing and other objects in view as well as ancillary advantages, this invention essentially comprises the novel center sill and its method of manufacture as illustrated by the accompanying sheets of drawings, hereinafter fully described, and particularly pointed out in the claims at the conclusion hereof.

In the drawings:

Fig. I is a plan view of a freight or hopper car including the novel center sill of this invention with parts broken away, and others in section, to better disclose underlying features.

Fig. II is a side elevation of the car with the left-hand portion in longitudinal section.

Fig. III is a broken perspective view of the improved center sill in accordance with the instant invention.

Fig. IV is a top plan view of one end portion

of the improved center sill drawn to a larger scale; and.

Fig. V is a side view of the same.

Fig. VI is a lateral section taken approximately as indicated by the arrows VI—VI in Figs. I and II.

Fig. VII is a similar section taken on the plane designated VII—VII in Figs. I and II.

Fig. VIII is a vertical section taken as indicated by the arrows VIII—VIII in Figs. IV and V.

Fig. IX is a like section taken on the plane designated IX—IX in the same Figs.

Fig. X is a similar section taken as indicated by the arrows X—X in Figs. IV and V; and,

Fig. XI is a further enlarged sectional detail showing a preferred manner in which the counterpart components of the improved center sill are integrally-united into a composite whole along their upper longitudinal edges.

Referring generally to Figs. I, II, VI, and VII it is to be observed there is therein illustrated a hopper type of railroad freight car for carriage of cement or the like, the same comprising an underframe of opposing side sills 1, and end frames 2, medially lengthwise whereof the center sill, of the instant invention and comprehensively designated 3, is incorporated. The body of the car is of plate construction and suitably subdivided by vertical transverse walls 4, into end hoppers 5, 6, with an intermediate hopper 7, said end hoppers having sloping walls 8 supported and reinforced by bolsters 9 in accordance with known practice; while the respective hoppers 5, 6, 7, have bottom outlets 10, 11, under control of drop doors 12. Although the illustrated car is of the multiple hopper type it is to be understood this invention is equally well adapted to single hopper cars, with equal advantages, as will be understood from the following disclosure.

The center sill 3, above referred to, and which forms the essential subject-matter of the present application for patent, as will be best understood from Figs. III—V and VIII—X inclusive, comprises a pair of counterpart plates suitably shaped or pressed to form parallel vertical webs 13, extending the full length of said sill. The upper parts of the webs 13 are suitably-bent or inwardly-angled along paralleling lines 14 to define opposed tapering flanges 15, extending substantially the full extent of the center sill 3, with their meeting 50 or confronting upper edges 16, Fig. XI, preferably united by an appropriate weld 17 into an integral structure. Similarly the lower portions of the webs 13 are appropriately bent or shaped to define horizontal flanges 18, which project out- 55

wardly relative to said webs to varying extent from the extreme ends of the sill 3, inwardly beyond the bolsters 9 to predetermined points 19, and then merge downwardly into the vertical webs 13 to points 20 outwardly-adjacent to the car sloping end walls 8, hereinbefore referred to. Thus it will be readily understood that the length of the center sill 3, intermediate the sloping end walls 8 of the car, as best appreciated from Fig. II, or where it projects upwards into the hoppers 5, 6 and 7, may be considered as of a continuous cross-section embodying vertical webs 13 with tapering flanges 15 merging upwardly to the longitudinal center line of the car, said webs and flanges being entirely devoid of any projections that might tend to interfere with the uniform discharge and free flow of the material transported in said hoppers, when the respective drop doors 12 are released. This feature or provision of good clearing angles and smooth surfaces leading down into the hopper outlets 10 and 11 will also be well understood from an examination of Figs. I, II and VII, wherein it is observable that the car end sloping walls 8 extend directly down to and are suitably secured on correspondingly-sloped flange portions 21 of the outlets 10, while the opposing inclined walls 22 of the hoppers 5, 6, are similarly attached thereto. In like manner the opposing walls 23, 24 of the hopper 7 are secured to the flange 25 of the outlet 11, while the vertical webs 13 of the center sill 3 are attached at 26 to the outwardly stepped flanges 27 of the several hopper outlets 10, 11, in a manner obvious from Fig. VII more particularly, so that no projections whatsoever are presented beyond the inner smooth surfaces of the several outlet walls that might tend to check the free flow or passage thereover of the material in the respective hoppers 5, 6 and 7, when dumping or emptying the car contents. Similarly the lower inwardly-sloping portions 28 of the several hopper side walls 29 are correspondingly attached to the confronting portions of the outlet flanges 21 and 25 in an obvious manner.

45 Referring again to the center sill 3, and more particularly to Figs. III-V as well as Figs. VIII-X which illustrate the end formation of said sill, it will be seen that between the points 19, 20 the intervening sill flange portions 18a taper downwardly and inwardly, or gradually merge from the horizontal to the vertical intermediate said points, the former of which points 19 being located well inside of the bolsters 9 and thus making the cross-section of the sill 3 where it passes through the hoppers 5, 7 and 6, continuously of the form shown in Fig. X, and it will be readily understood that, by countersinking the rivet holes 30 therein, uninterrupted smooth exterior surfaces throughout the parts of the sill 3 extending upwards into the hoppers 5, 7 and 6, are effectively provided for. Furthermore the sill flange horizontal portions 18b outside of the bolsters 9 are also tapered from the points 31 exterior of the bolster base flanges 32 to their extremities or free ends, whereat the sill 3 is suitably shaped to rectangular or inverted-channel section 33, for reception and attachment of the conventional draft gear and striker castings, not shown. It is also to be remarked that the sill upper opposing angled flanges 15 from a point 34, well to the rear of each bolster 9, are expensively flattened down, as at 35, to a common inclined plane for emergence into the upper horizontal face of the section 33; or, in other words, 75 the outer and cross-sectional shape of the

sill opposing plate components merge outwardly with respect to the points 34, from a Z section having a vertical web 13 with the top flange 15 upwardly-angled relative to the lower flange 18, downward to the sill end sections 33 whereat the 10 web 13 remains vertical but the flattened portions 35 are brought horizontal in parallelism with the sill end portions 18b of the side flanges 18. Thus it will be readily understood that the center sill ends outside of the bolsters 9 are gradually stiffened from the points 34 towards the ends of the car, and that they merge outwardly from the cross-section of Fig. X into what may be termed true Z-shape at the part which houses the draft gear housing and striker castings. 15

Furthermore it is to be understood that the transition to the flattenings 35 from horizontal to vertically inclined may be located anywhere between the bolsters 9 and the car end; while the transition of the flanged bottom portions 18a 20 may be located anywhere between said bolsters and the proximate hopper end walls 8. Also it is to be noted that for ordinary hopper cars of the type indicated hereinbefore, the novel center sill of this invention can be easily shaped 25 from two half-inch plates of about thirty-inches wide and running the full length of the car. The section of the center sill 3 intermediate the points 34 is such that the transverse width of the hoppers 5, 6 and 7, is not encroached upon by the 30 flanges 18, while said sill forms a part of the respective hoppers and needs no shrouding to provided the desired shape.

From the foregoing description it will be appreciated that the present invention fully accomplishes the stated objects, together with others apparent from an understanding of this disclosure; and while there has been shown and described a preferred manner of carrying the same into practical effect, it is to be understood 40 such disclosure is not to be considered as limiting said invention, the scope whereof is specifically defined by the following claims.

Having thus described my invention, I claim:

1. A center sill comprising counterpart continuous components shaped to define substantially paralleling webs with an intervening ridge and an opposed continuous opening, and said components also embodying lateral flanges extending inwardly from the ends to a predetermined extent and therefrom merging into the paralleling webs. 45

2. A center sill comprising counterpart continuous components shaped to define substantial parallel webs with an intervening upper ridge and an opposed lower continuous opening, said plates having lower outwardly-directed lateral flanges extending inwardly from the ends thereof to predetermined points with their confronting portions merging into the paralleling webs, and the sill having its ends taperingly expanded down to somewhat inverted U-shape cross-section. 50

3. A center sill in accordance with claim 2 wherein the lateral flanges are horizontally disposed and include inner portions merging downwardly therefrom into the paralleling web lower edge portions of said sill. 65

4. A center sill comprising counterpart continuous plates shaped to define parallel vertical webs defining a lower continuous opening with an intervening ridge along the upper confronting edges whereat said plates are integrally-united, said sill having lower horizontal outwardly-directed flanges extending inwards from the ends thereof 70

to predetermined points with confronting sections merging downwardly into the vertical webs, and said sill also having end sections of substantially rectangular cross-section with adjoining portions of the ridge aforesaid inclinedly flattened to merge into such end sections.

5. A center sill in accordance with claim 4 embodying end sections of predetermined length including spaced vertical webs connected by upwardly-angled opposing portions and lower outward horizontal flanges, and such sections taper downwardly into terminal ends with the upwardly-angled portions merged into parallel relation with respect to the lower flanges aforesaid.

10 15. A center sill in accordance with claim 4 wherein the sill lower horizontal flanges are outwardly reduced in width from predetermined points inwardly of the sill ends.

20 7. A center sill for a railway car comprising spaced sill plates having substantially paralleling webs defining a continuous open bottom lengthwise thereof, said plates having top flanges united together at their free edges, and said flanges and webs forming varying angles with each other 25 along the length of the sill plates.

25 8. A center sill for a railway car comprising spaced plates having substantially paralleling webs defining a continuous open bottom lengthwise thereof and with top and bottom flanges, the top flanges of each plate being united at their free edges, and the top and bottom flanges of each plate forming varying angles with the web along the length thereof.

30 35. 9. A center sill for a railway car comprising a pair of spaced sill plates having substantially vertical webs defining a continuous open bottom lengthwise thereof, said plates having top flanges integrally united at their free edges, and said plates being formed to varying cross-sectional shapes along the length thereof.

40 45. 10. A center sill for railway hopper cars comprising a pair of sill plates of substantially uniform width and bent to varying cross-sectional shapes at points along the length thereof, said plates being integrally joined at their top edges and being symmetrically disposed with respect to the line along which they are joined.

50 55. 11. An open-bottom center sill for railway hopper cars comprising a continuous plate-like structure bent to varying cross-sectional shapes along the length thereof to afford spaced vertical webs bridged at the ends of the structure by a substantially flat top member, and at the central portion of the structure by an inverted V-shaped member.

60 55. 12. An open-bottom center sill for railway hopper cars comprising a continuous plate-like structure bent to varying cross-sectional shapes along the length thereof to afford spaced vertical webs bridged at the ends of the structure by a substantially flat top member and at the central portion of the structure by an inverted V-shaped member, said flat top member gradually merging

into said inverted V-shaped member intermediate the ends and central portion of the structure.

5 13. An open-bottom center sill for railway hopper cars comprising a continuous plate-like structure bent to varying cross-sectional shapes along the length thereof, said structure being characterized by spaced vertical webs extending throughout its length, and having at its end portions a flat top member bridging said webs and outwardly extending bottom flanges and having at its central portion an inverted V-shaped top member bridging said webs.

10 15. 14. An open-bottom center sill for railway hopper cars comprising a continuous plate-like structure bent to varying cross-sectional shapes along the length thereof, said structure being characterized by spaced vertical webs extending throughout its length, and having at its end portions a flat top member bridging said webs and outwardly extending bottom flanges and having at its central portion an inverted V-shaped top member bridging said webs, said flat top member gradually merging into said inverted V-shaped member and said outwardly extending flanges gradually merging into said webs at the regions intermediate the ends and central portion of the structure.

20 25. 15. In a railway car, a body bolsters, and a center sill comprising spaced sill plates having substantially parallel vertical webs defining a continuous open bottom lengthwise thereof, said plates having top flanges joined together at the longitudinal center line of the car, said top flanges being disposed in a horizontal plane at the regions of the center sill outside the body bolsters, and said top flanges being of inverted V-shaped formation in the region of the center sill between the body bolsters.

30 35. 16. In a railway car, body bolsters, and a center sill comprising spaced sill plates having substantially parallel vertical webs defining a continuous open bottom lengthwise thereof, said plates having top flanges integrally joined at the longitudinal center line of the car, said sill plates being of substantially Z-shaped formation at the regions of the center sill outside the body bolsters, and said top flanges having an inverted V-shaped formation at the region of the center sill between the body bolsters.

40 45. 17. In a railway hopper car including body bolsters and end slope walls, a center sill comprising spaced sill plates having substantially parallel vertical webs jointly defining a continuous open bottom lengthwise thereof, said plates having top flanges joined together at the longitudinal center line of the car, said top flanges being disposed in a horizontal plane at the regions of the center sill outside the body bolsters, and forming an inverted V at the region between the end slope walls and gradually merging from the regions between the end sill and the end slope walls.
